United States Patent

Des. 241,524
Patented Sept. 21, 1976

241,524

TIMER OR SIMILAR ARTICLE

Olle E. Haggstrom, Trumbull, Conn., assignor to
General Electric Company

Filed Nov. 13, 1974, Ser. No. 523,234

Term of patent 14 years

Int. Cl. D10—03

U.S. Cl. D10—40

FIG. 1.

FIG. 2.

FIG. 3.

FIG. 4.

FIG. 5.

FIG. 1 is a front perspective view of a timer or similar article showing my new design;

FIG. 2 is a right side elevational view thereof, the left side being substantially a mirror image thereof;

FIG. 3 is a rear elevational view thereof;

FIG. 4 is a top plan view thereof; and

FIG. 5 is a bottom plan view thereof.

I claim:

The ornamental design for a timer or similar article, as shown.
